UNITED STATES PATENT OFFICE

BURDETT LOOMIS, OF HARTFORD, CONNECTICUT, ASSIGNOR TO LOOMIS UTILIZATION COMPANY, OF EAST ORANGE, NEW JERSEY, A CORPORATION OF NEW JERSEY.

BEATING-ENGINE AND EXTRACTING APPARATUS FOR MAKING CELLULOSE.

1,108,593.

Specification of Letters Patent. Patented Aug. 25, 1914.

Application filed November 27, 1912. Serial No. 733,808.

To all whom it may concern:

Be it known that I, BURDETT LOOMIS, a citizen of the United States, residing at Hartford, in the county of Hartford and State of Connecticut, have invented certain new and useful Improvements in Beating-Engines and Extracting Apparatus for Making Cellulose, of which the following is a specification.

This invention relates to a closed beating engine and connecting apparatus for digesting woody material and plants to make cellulose, and preparing finished paper stock directly in the engine; also for saving extracted natural constituents, such as tannic acid, fatty acids, volatile and other oils, gums and resins, and re-using fatty acids and other solvents in a subsequent operation.

The principal object of my invention is to provide an improved construction of beating engine, in which woody and other fibrous material may be reduced to pulp or cellulose under pressure, and in which the material may be caused to circulate while subjected to the action of a beating drum and blades till a washed, clean and bleached cellulose is prepared ready for paper making.

Another object is to provide special means in a closed digester and beating engine, for causing a forced circulation of extracting and dissolving liquor and fibrous material or pulp, whereby every part of the fibrous material may be repeatedly subjected to the action of the beating drum and blades, and the mass of material agitated for facilitating the extraction and removal of oils, gums and resinous matter.

Another object is to provide an apparatus, including a closed beating engine and extractor for circulating hot water or solvent liquor, reheating such water or liquor, separating and storing watery extracts, such as tannic and other acids, volatile and other oils, and resinous and gummy matter from wood and plants whereby great economy may be effected and improved products obtained.

Different kinds of wood and plants contain a variety of constituents, such as tannic and other acids, gums, wax, turpenes, oils and resinous substances, according to the character or kind of wood or plant, which substances are not useful or desirable

in cellulose for making paper, and are, in fact, detrimental thereto,—but which, if separated from the wood and from one another, are quite valuable for use in the arts, and which when separated, leave the fiber of wood or plants in the cleanest and best condition for making superior pulp or cellulose, with a reduced expenditure of time and labor and a reduced percentum of chemicals, heretofore required for that purpose.

My apparatus is especially adapted for extracting and separating the various useful constituents and utilizing them as far as possible in making cellulose.

The matter constituting my invention will be defined in the claims.

I will now describe my apparatus by reference to the accompanying drawings, in which—

Figure 1, represents a sectional elevation of a closed beating engine, and extractor constructed in accordance with my invention. Fig. 2, represents a sectional elevation of a beating engine and connecting apparatus for separating and collecting extracted material, a reheater for solvent liquor, a gas heater and connections, and other devices for collecting and saving useful products.

In the apparatus I provide seven principal parts or devices consisting of a beating engine and extractor 1, an expansion and decomposing chamber 30—30^a, heating coils 36 located in a furnace below the bottom of engine 1, a condenser 32, a gas heating coil 44 in a furnace, a gas force pump 62, and a disintegrator tank 68, these parts being suitably connected by valved pipes, and a circulating force pump being connected in the system.

The closed circulating and beating engine 1, may be constructed of cast iron or other suitable metal, and has four principal body portions, consisting of the lower transverse horizontal body 2—2^b, end connections 3—4^a, an upper inclined conveyer pipe or trunk 4, 100 and an upright end 5, suitably connected together to form a circulating chamber for fiber-material and treating liquor or water. To one end of the drum-chamber 2^a is connected a T 2^b, having an opening and a cover plate *a* for permitting inspection, or for other desired purpose. To the other end of chamber 2^a is connected a corner T 3, having

a blow off or discharge pipe 3^a. To this T is connected an upper cross 4^a which in turn is connected to the inclined transverse conveyer pipe or trunk 4. These castings are bolted together at their flanges. The cross casting 4^a has a top opening which is closed by a cover plate 4^b, also an outer end opening which is closed by the thrust plate 4^c, having a socket 15, containing a thrust collar and washer for the end of shaft 13. To the trunk 4, is connected an angle cross casting 6, to which is also connected the top mouthpiece 6^a and the upright pipe connection 5, which connects at its lower end with the lower corner T connection 5^a which has a supporting web 5^b. The upper flanged end of the mouthpiece is provided with a circular groove for receiving the cover 7, which is provided with a circular rib to make a tight joint with said groove. The cover will be secured in place by bolts 7^a and is provided with a screw-eye 7^b. The casting 6 is provided with a circular shoulder 6^b within the mouthpiece 6^a, for supporting a perforated screen plate or sieve 10. To the cover 7 is secured a pipe or rod 9, having a flange at its lower end, to which is connected the plate 10, so that the said plate may be removed with the cover. The mouthpiece is provided with a discharge pipe connection 8, connecting with a discharge pipe 8^a, which connects with the expansion and depositing chamber 30 and is provided with a valve b.

In the pipe or trunk 4 is placed a screw conveyer 12, having a shaft 13 resting at its lower end in the socket 15, and passing at its upper end through a stuffing box and plate 14. In practice a belt wheel or any suitable gear wheel will be secured to shaft 13 for turning the screw-conveyer.

The corner casting 5^a is provided with a pipe connection 16 for the return circulating pipe 39 leading from the top of the heating coil. Within the casting 5^a is extended an injecting pipe 17, as a continuation of the return pipe 39. This serves as one of the means for causing a forced circulation through the beating engine.

In the chamber 2^a is mounted a beating drum 18 on a shaft 19 in a journal box 20 in a well known manner. Below the drum, in a suitable casing is placed an adjustable bed plate 21, having the usual knives or blades, and made adjustable toward or from the drum by special adjusting mechanism 22 in a casing 23. A clean-out door 24 is provided in the lower part of the drum chamber. The upper wall of the drum chamber 2^a is suitably curved to conform approximately to the curve of the drum, but so as to approach it closer at the upper corner 2^c of the chamber. The drum will revolve in the direction of the arrows. The opening between the upper wall and the

drum is flaring from the narrow slit 2^c to the wide opening 2^d. The construction of the upper wall serves to prevent most of the fiber material from circulating around with the drum.

To the mouthpiece 6^a is connected a water and vapor discharge pipe 8^a, having a valve b, which connects with an expansion and depositing chamber, 30-30^a, at the top of which connects a vapor discharge pipe 31, 75 having a valve c, leading to a condenser 32.

The expansion and depositing chamber 30-30^a is of a suitable height and diameter to provide for expansion of the vapors and partial cooling of the liquor to facilitate deposit of resinous or gummy material. At the lower end the chamber is made with tapering walls terminating with a discharge pipe having a valve g for drawing off gummy or resinous matter.

A steam coil 38 is placed in the lower end of the depositing chamber for melting gummy or resinous material in case it becomes cold and hardened. At about the middle height of chamber 30-30^a is placed a separating dome or hood 33 which may be attached at its edges to the wall of the chamber, as shown in Fig. 2. In this construction the outlet pipe 34 connects with the wall of chamber 30^a at the top of the dome and is 90 provided with a valve e. The dome 33 is located below the connection of the water and vapor discharge pipe 8^a from the engine and extractor 1 and provides a vapor expansion chamber or space 30 above it, and a depositing or catch-all chamber or space 30^a below it. This dome acts as a deflector and separator to cause the rosin or gummy matter to be deposited in the bottom of the chamber while the water or treating liquor flows up into the dome and thence off to the circulating pump 35.

A positively acting rotary pressure pump 35 is preferably used, though some other kind of positive pressure pump may be employed. A discharge pipe 35^a connects with the pump and leads to the lower end of a series of heating coils 36 suitably supported in a furnace 37. These coils are connected in a series by means of return bends h which extend through the wall of the furnace. Near the bottom of the furnace is provided a perforated arch 37^a for distributing the gas flame and protecting the lower heating coil. A fire chamber is provided below the arch 37^a. Gas is preferably burned in the fire chamber and is supplied by a pipe 40 having a valve k' and a burner k of any suitable kind in the fire chamber.

In order to secure satisfactory heating and circulation of treating liquid through the apparatus, the heater is located so that the top thereof is below the bottom of the engine and extractor 1.

To the top of the heating coil is connected a return pipe 39 of the circulating system,

and this pipe is also connected to the pipe connection 16 at the bottom of the engine 1. The pipe 39 is provided with a check valve f' . A check valve f is also placed in the 5 lower end of pipe 35^a at its connection with the coil. These check valves prevent back flow of water from the engine. A water supply pipe 41, having a valve l connects with the mouthpiece or may connect at other 10 desired part of the apparatus.

A second heating furnace 42, containing 15 a gas heating coil 44 is provided for heating gas to be used, if necessary, in drying the contents of the beating engine after the material has been treated with a solvent solution. A gas supply pipe 43, having a valve n supplies a burner o in the furnace. A gas supply pipe 45, leading from a gas-holder 46, and having a valve p connects 20 with the heating coil 44. A pipe 47 leads from the coil into the lower part of the engine 1, and is provided with a valve q . An outlet pipe 50, having a valve t , connects with the mouthpiece 6^a, and leads to a second 25 condenser 56 from which a pipe 57 leads to a rotary exhauster 58. The condenser is provided with a draw-off pipe and valve w . A pipe 59, having a valve r leads from the exhauster and connects with the pipe 30 47^a, connecting with pipe 45. A branch pipe 60, having a valve x connects pipe 59 with the holder. Gas drawn from the engine and extractor may thus be returned either directly to the heating coil or to the holder. 35 Cold gas may also be passed from the holder through pipe 47^a, having a valve p' , into the beating engine.

A compression pump 62 may be used to draw gas directly from the holder 46 40 through pipe 66, or hot gas from the heater through pipes 66, 66^a and 47, and discharge it through pipe 63, and branch 64 in the top of an elevated feed tank 61, for holding alkaline chemical or bleaching liquor. The pipe 66^a has a valve c'' . A pipe 62^a, having a valve z connects tank 61 with pipe 50 leading to the mouthpiece 6^a of the engine. The tank 61 is provided with a cover y and its supply pipe 64 is provided with a valve a' . 45 A branch pipe 65, having a valve b' connects with a pipe 63 and with the mouthpiece 6^a for admitting gas under pressure directly to the beating engine when required for blowing out the cellulose or other contents.

To pipe 39, leading from the heating coil 36 is connected a blow-off pipe 52, having a valve s and connecting with a storage and settling tank 51. To pipe 39 is also connected a draw-off pipe 53, which connects by a 50 branch pipe and valve s' with a tank 54 and by a second branch pipe and valve t' with another tank 55. These tanks 54-55 are provided respectively with faucets u and v .

A pulp receiving and disintegrating tank 56 55 is connected by a blowoff pipe 3^a having

a valve l' to the discharge pipe at the bottom of the engine and extractor 1, and is provided in its top plate with a target 69 against which the pulp is blown for separating and disintegrating it. The tank is also 70 provided at the top with a purge pipe 70 having a valve 71 for the escape of vapors. Across the lower end of tank 68, about one-fourth of its height from the bottom, is secured a grid and filter cloth 72, providing 75 a compartment 73 below for receiving liquor, and to the bottom is connected a drain pipe 74, having a valve d' , for discharging the liquor. A pipe 75 connects with the bottom of the tank and extends up into compartment 73 where its upper end is provided with a plug 76, and this pipe serves for discharging the pulp after having been drained. A gas pipe 65^a, having a valve e' , leads from a compression pump 62 and connects with tank 68 just above the pulp discharging nozzle 1" for supplying gas under pressure to carry off much of the watery vapor at the time the pulp is blown against the target 69, so that much of the black 90 liquor, which would otherwise settle with the pulp onto the filter cloth, will be taken up and carried off with the gas. As a result of this operation there is left less liquor to wash out of the cellulose and, therefore, the 95 cellulose will be much cleaner when removed from the tank. The purge pipe 70 will preferably connect by pipe 77 having valve h' with a condenser 78 for separating water or any other condensable matter from the gas. 100 The gas, freed from condensable matter, will be returned to the holder or to a heater.

By constructing the beating engine and extractor as shown in Fig. 1, I provide for effectively circulating the fiber material and 105 solvent, or other treating liquor, and repeatedly subjecting them to the beating and grinding action of the drum and blades of the bed plate. Four parts or devices are provided for aiding circulation, consisting 110 of the revolving drum 18, the inclined screw-conveyer 12, in pipe 4, the down-take pipe 5, in which the weight of material aids by gravity; and the injecting pipe 17 leading from pipe 39 and the force pump 35. These 115 parts work harmoniously together, and if the drum is stopped the other parts would still act to circulate the treating liquor through the fiber material for extracting tannic and fatty acids, volatile oil, other 120 oil, gums, resins, etc., or for circulating a washing or bleaching liquid through the material.

By heating wood to a moderate temperature, ranging between 215° and 245° F., decomposition is set up, resulting in the formation of a number of acids of the fatty acid series and by raising the temperature there are formed other fatty acids. The formation of fatty acids, among which acetic 130

acid appears in largest quantity, commences, according to Gillet, at 255° F. Other fatty acids are formed, such as formic acid, propionic acid, butyric acid, valeric acid, etc., at the above and higher temperatures. Simultaneously with the formation of these acids, carbonic acid, carbonic oxide and methane are evolved from the wood, and these bodies in a nascent state may act upon the acids so that the latter may undergo decomposition by more vigorous beating and a large number of products of decomposition may be formed. Among such products are found methyl alcohol (wood spirits), acetone and metacetone, methyl acetic ether, aldehyde and dimethyl acetal. I have discovered that these above mentioned fatty acids, gases and other products of decomposition, when diffused in hot water, are an excellent solvent for the cellular structure, the gummy and resinous material found in wood and plants, and that, if the mixture or solution is circulated in contact with the wood or plants to be treated the contained resinous matter, oils, and turpentine or other volatile oil will be quickly liberated and may be drawn off with circulating water. The turpentine and more volatile oil will pass off in the form of vapor and will be condensed, and the rosin and gum will pass off in a melted semi-liquid condition, and will be deposited and recovered. I have also discovered that the fatty acids and other solvents may be most effectively and economically produced and diffused in water by first heating fresh water and circulating it in contact with the wood, or plants to be treated at gradually increasing temperatures, ranging from 212° to approximately 300° F. The volatile solvent is readily extracted from the wood or plants and diffused in the water and the mixture is passed from the engine and extractor through a heater where the temperature is raised and is then circulated up through the wood or plants, in the engine and extractor. The circulation of the water and solvent in contact with the wood or plants and through the heater, the temperature being gradually increased, is continued till the solvent has liberated the turpentine, oil, resinous and gummy matter, and these valuable products have been recovered. The treatment may be continued for six to twelve hours, according to the character of the wood or plants and the temperature of the treating liquor.

In the operation of preparing fatty acid solvent from the wood or other fiber material, hot gas, such as wood-gas or producer-gas, heated to a temperature between 200° F. and 300° F. in the coil 44, may be admitted to the engine and extractor through pipe 47 and circulated alone or with a suit-

able proportion of water through and in contact with the fiber material. By means of this circulating warm or hot gas for some time,—thirty to ninety minutes—in contact with the fiber material the fatty acids, gases and other solvents will be extracted and formed from the wood and mixed with the water or other liquor. At the time the warm or hot gas is circulated, the volatile extract is preferably not drawn off and condensed, but is retained in the circulating fluid for its solvent action on the cellular structure and on the gummy and resinous matter. The extraction of fatty acids and other solvents by gas is rapid and is quite effective in connection with circulated water, when conducted substantially as above described.

I preferably first remove tannic acid from the wood or plant material, as it can be extracted at a low temperature, between 120° and 170° F., and if left in the wood during the pulping operation, combines with the fiber, imparting thereto a dark color, and cannot then be washed out with water alone, but must be removed by alkali and bleaching agents, entailing additional expense.

In operating the apparatus, the engine and extractor 1, is partially filled with chips of wood or cut fibrous plant material through the mouthpiece 6^a, at which time, the cover 7, and screen 10, will be removed. The screen plate 10, will be attached to the flange of pipe 9, so that the screen may be removed with the cover. After the engine is suitably charged the cover will be secured in place by the bolts 7^a. The whole system is now filled with water or a solvent liquor admitted by pipe 41 and caused to rise to the level of the discharge pipe 8^a, at its connection with the expansion chamber 30. Gas may now be admitted to, and ignited at the burners k' below the coils, and the circulating force pump 35 is started. This causes circulation of water through the heating coils and thence up through the engine and extractor, the water being injected through pipe 17, for causing better circulation through the engine and extractor. The water is circulated at a temperature between 120° F. and 170° F. through the body of chips or plant material for first removing tannic acid. Circulation of water at this low temperature is continued until all, or most of the tannic acid has been extracted, then this acid solution is drawn off into a tank 54, by opening the valve s' in pipes 53.

The system is again filled with water, or a fatty acid solvent solution made by a previous treatment of wood chips, and the pump 35 again put in motion, and the heat may be gradually increased in the furnace 37. As the circulating water becomes heated, approximately to 212° F. some of

the fatty acids are produced and passed with the water into the heating coils. As the temperature of the water is gradually increased other fatty acids, gases, and products of decomposition are formed and diffused through the water. The hot circulating water and the solvent fatty acids soon commence to dissolve the cellular structure and release turpentine, or volatile oil, and 10 gummy or resinous matter from the wood-chips or plants. The turpentine and other volatile oil vapor passed with the water or liquor into chamber 30-30^a, where the volatile vapors separate and fill the upper part 15 of chamber 30, from which they pass off through pipes 31, to the condenser 32, where condensation is effected. At the same time the resin or gum which has been released from the wood or plant material is passed 20 with the water down past the separating dome 33, and the resin or gum is deposited in the lower part of chamber 30^a, while the water passes up through the dome 33, and thence by pipe 34, the pump 35 and pipe 35^a 25 into the bottom of the heating coils 36, and thence through pipe 39 into the bottom of the engine.

By circulating the hot water up through the body of material in the engine the resinous or gummy matter is carried upward and floated off with the water through pipe 8^a into the expansion and depositing chamber 30-30^a.

The circulating hot water or solvent liquor agitates the body of chips or plant material and prevents packing, and continuously carries away the extracted material so as to continuously bring fresh liquor into contact with the chips, thereby 35 effectively exerting its solvent action on the cellular structure so as to release the gummy and resinous constituents. In the expansion and depositing chamber 30-30^a the liquor is partially cooled and quieted, so that the 40 rosin or gum becomes hardened and will readily settle to the bottom of chamber 30^a.

The temperature of the water or liquor may be gradually raised in the heating coils to approximately 300° F., and it will be 45 come charged with an increasing percentage of fatty acids, gases, etc., and these act with increasing energy to dissolve, release and extract the turpentine, oil, resinous and gummy matter from the material until it is 50 substantially free from such constituents. The operation may be continued for a period varying from 6 to 12 hours, according to the character of the wood or plant being treated.

During the above described operation of 55 extracting constituents from the fiber material the screw conveyer 12, may be operated to assist circulation and agitation of material in the engine. The pump 35 will also operate to force liquor through the

heater and thence through the injector pipe 65 17, thereby causing circulation thereof through the fiber material and up to the overflow pipe 8-8^a leading from the mouth-piece to the expansion and depositing chamber 30-30^a.

At suitable intervals, the valve *g* may be 70 opened and the resinous or gummy matter discharged from the chamber 30^a, but this may be mostly discharged at the end of the operation.

At any suitable stage in the operation, when the chip or plant material has become sufficiently softened and partially freed from gummy or resinous material the beating drum 18 may be set in motion and the material subjected to beating, rubbing and grinding while at the same time the hot solvent liquor is circulated through the engine.

When the treatment of the material in the 85 engine is completed, the valve *b* in pipe 8^a may be closed and the blow off valve *s* opened, permitting the water or liquor containing the fatty acid to be blown off into the storage and settling tank 51, where it 90 is reserved for treating a succeeding charge of fiber material in the engine and extractor. This blowing off operation may be facilitated by admitting compressed gas from pump 62 through pipe 63 into the top of 95 the engine. The wood chips or other fibrous material in the treating engine will now be practically free from gum, resin, and oily matter, and the pores will be open so as to be readily permeated by caustic- 100 soda or other solution.

The cleaned fibrous material may be conveniently reduced to cellulose directly in the engine, which now becomes a digester and beating engine, by admitting fresh water through pipe 41 and the desired per cent. of caustic soda solution of sulfite of soda from tank 61. The beater drum 18, and the circulating devices will be put into operation at the desired stage of the process. The circulating pump 35 will be put into operation and the liquor caused to circulate in the direction of the arrows through the heater 36 and up through the material till digestion and reduction to 115 pulp or cellulose is completed. The temperature may be raised to 250° F., or higher if required, and at intervals more alkaline solution admitted from tank 61. Gas under pressure may be admitted by pipe 64 into 120 the top of tank 61 for forcing the alkaline solution into the engine. Owing to the preliminary thorough preparation of the chips, or fiber material the percentage of caustic soda, sulfite or soda or other chemical 125 used for digesting the fibrous material, will be very much smaller than that required in the ordinary process. The heat and pres-

sure will be much lower and the time will be much reduced for reducing the material to a good strong fiber pulp or cellulose.

The cellulose prepared as above described, 5 freed from gums and resins, will be bleached to the desired extent with a comparatively small per cent. of chlorid of lime or other bleaching agent and thus great economy effected, while the cellulose will have greatly 10 increased strength of fiber. The low heat and pressure employed in the digester also contribute to the strength of the fiber in the cellulose.

Owing to the reduced amount of caustic 15 soda and the shorter time required in digesting the prepared chips the fiber of the cellulose will have greater strength than that produced in the usual way.

After reduction of the fibrous material, 20 by digestion with alkali or alkaline salt, to pulp or cellulose, has been completed, that is cooked in the engine, I may draw off the alkaline liquor through pipe 3^a, and admit fresh warm or cold water through pipe 41 25 to the digester and engine and circulate such water repeatedly through the cellulose by means of pump 35 and conveyer 12 for washing out the alkali and dissolved or saponified oily or resinous matter. The first 30 wash liquor may be drawn off and fresh water again admitted and circulated till the cellulose is sufficiently clean. The finished cellulose may be blown off through pipe 3^a to the disintegrating tank 68. 35 The cellulose having been produced, gas under pressure is supplied from pump 62 through pipe 65 to the top of the engine and then valve 7' is opened and the cellulose is discharged through blow-off pipe 3^a 40 and nozzle 7'' against the target 69 in the top of tank 68. Here the particles which adhere together will be disintegrated and separated. At the same time gas under pressure will be admitted through pipe 65, 45 just above the discharge nozzle 7'', so as to catch the spray of liquor, containing coloring matter and some residue of gummy matter, and carry it out through the purge pipe 70. The top valve 71 may be open, so as to 50 blow the gas and vapors into the open air, but said valve will preferably be closed and the gas and vapors conducted by pipe 77, its valve 7' being open, to a condenser 78, where the liquor vapor will be condensed, 55 while the gas will be freed and returned to the holder, or to a heater to be again heated and then compressed to be used over again for blowing out-colored liquor vapor. Any liquor which drains from the pulp 60 through the filter cloth 72 will be drawn off from compartment 73 as required. The pulp or cellulose may be discharged from tank 68 by opening valve 76 in pipe 75, into a bleaching or other tank.

By first extracting and removing the tannic acid from the wood, I prevent discoloration of the cellulose. The tannic acid is left in the treating tank combines with the fiber and becomes fixed so that it cannot be removed by ordinary washing, but must be 70 removed by chemical treatment, entailing additional expense for chemicals and requiring additional time for treatment.

Strength, toughness and elasticity are characteristic of the fiber in the cellulose 75 produced by my process.

Having described my invention, what I claim, and desire to secure by Letters Patent is:—

1. A closed heating engine and extractor 80 having a drum and bed plate provided with blades and independent means including a screw conveyer and an injector inlet pipe for causing circulation of fiber material or pulp and treating liquor.

2. A closed beating engine and extractor having a beating drum, a vertically adjustable bed plate and separate means including a screw conveyer and a liquid injector feed pipe for causing circulation of fiber material 90 and treating liquor.

3. A closed beating engine and extractor having a horizontal body provided with a beating drum and bed plate, an inclined pipe or trunk above said body and drum and connecting at one end with said body and drum and having means for conveying material and causing circulation in the engine, a down take pipe connecting with the other end of the body and said inclined pipe connecting at its 100 other end with the upper end of the down-take pipe.

4. A closed beating engine and extractor having a horizontal body containing a beating drum and bed plate, an inclined pipe or trunk connecting at its lower end with the body, a down-take stand pipe connecting the elevated end of said inclined trunk with the body and a conveyer device in the inclined trunk for causing circulation of material 110 and liquor in the engine.

5. A beating engine and extractor having a horizontal body containing a beating drum and bed plate, an inclined pipe or trunk connecting at its lower end with one end of the body, a mouth piece having a feed opening and cover connecting with its upper end, a down-take stand pipe also connecting with said upper end and with the other end of the body, and means for causing circulation 115 of material and liquor in the engine and extractor.

6. A beating engine and extractor having a horizontal body containing a drum and bed plate, an inclined trunk connecting at its lower end with the body at the discharge side of the drum, a stand pipe connecting the upper end of the trunk with the body at 125

the intake side of the drum, and a screw-conveyer in said inclined trunk for causing circulation of material and treating liquor.

7. A beating engine and extractor having a horizontal body containing a drum and bed plate, an inclined trunk connecting at its lower end with the body at the discharge side of the drum, a stand pipe connecting the upper end of the trunk with the body at 10 the intake side of the drum, a mouth piece having a feed opening and cover, a strainer and a discharge pipe mounted at the upper end of the stand pipe and trunk, and means for causing circulation of material and 15 liquor.

8. A beating engine and extractor having a horizontal body containing a drum and bed plate, an inclined trunk connecting at its lower end with the body at the discharge 20 side of the drum, a stand-pipe connecting the upper end of the trunk with the body at the intake side of the drum, a mouth piece having a feed opening and cover, mounted above the stand pipe, a conveyer in the inclined trunk, and an injecting inlet pipe connecting with the body on the intake side of 25 the drum for the purpose described.

9. A beating engine and extractor having a horizontal body containing a beating drum 30 and bed plate, an inclined pipe or trunk connecting at its lower end with the body, a down-take stand pipe connecting the elevated end of said inclined trunk with the body and an injector inlet pipe, conveying 35 fluid under pressure, connecting with a part of the engine and extractor for causing circulation therein.

10. A beating engine and extractor having a horizontal body containing a beating drum 40 and bed plate, an inclined pipe or trunk connecting at its lower end with the body, a down-take stand pipe connecting the elevated end of said inclined trunk with the body and an injector inlet pipe projecting 45 into a part of the engine, and a supply pipe having means for forcing fluid under pressure through said injector for causing circulation in the engine and extractor.

11. A closed beating engine and extractor 50 having a horizontal body containing a beating drum and bed plate, an inclined circulating pipe or trunk connecting at its lower end with the body, a down-take stand pipe connecting the elevated end of said inclined trunk with the body, a discharge pipe connecting with the upper part of the engine, a heater connecting with said pipe, an injector inlet pipe connecting the body, a pipe leading from the heater and connecting with said injector pipe and means in the inclined pipe for causing circulation 60 of fluid through the heater and engine.

12. A closed beating engine and extractor

having a horizontal body containing a beating drum and bed plate, an inclined circulating pipe or trunk having a conveyer connecting at its lower end with the body, a down-take stand pipe connecting the elevated end of said inclined trunk with the body, a discharge pipe connecting with the upper part of the engine, a liquid injector pipe connecting with the body, a forcing device and a heater connecting with said discharge pipe and a return pipe connecting with said injector at the lower part of 75 the engine for causing circulation through the heater and engine.

13. A closed beating engine and extractor having a horizontal body containing a beating drum and bed plate, an inclined circulating pipe or trunk connecting at its lower end with the body, a down-take stand pipe connecting the elevated end of said inclined trunk with the body, an injector inlet pipe connecting with a lower part of 80 the engine, a liquor discharge pipe connecting with an upper part of the engine and extractor, a heater connecting with said pipe, a return pipe connecting the heater with said injector at the engine, and separate means for causing circulation of treating liquor through the engine and heater.

14. A closed beating engine and extractor having a horizontal body containing a beating drum and bed plate, a circulating pipe 95 or trunk above the body and drum and connecting at one end with one end of the body and at the other end with the other end of the body, and means in said trunk for causing circulation of material and liquor.

15. A closed beating engine and extractor having a horizontal body containing a beating drum and bed plate, a transverse pipe or trunk above and connecting at each end with the ends of the body, a conveyer in 105 said trunk, and means for feeding the engine with fiber material and treating water or liquor.

16. A closed beating engine and extractor having a horizontal body containing a beating drum and bed plate, an upper transverse pipe or trunk connecting at each end with the ends of the body, a mouth piece, having a feed opening and cover, connecting with the trunk, and a conveyer in the 115 trunk for assisting circulation of material and liquor.

17. The combination with a closed beating engine and extractor, of means for supplying hot water or liquor thereto, including an injector inlet pipe, a discharge pipe for liquid and vapor connecting near the top of the engine, a heater and a return circulating pipe connecting with said injector inlet pipe for supplying liquor to 125 the engine and assisting circulation therein.

18. The combination with a closed beating engine and extractor, of a pulp receiving and disintegrating tank; a gas compression pump connecting with the engine and with the disintegrating tank, a blow-off pipe of the engine having a discharge nozzle in said tank, the discharge end of the gas pipe being adjacent to said nozzle, whereby a blast of gas may be blown

across the stream of discharged pulp or 10 cellulose.

In testimony whereof I affix my signature in presence of two witnesses.

BURDETT LOOMIS.

Witnesses:

E. B. CLARK,
BENNETT S. JONES.
